UNITED STATES PATENT OFFICE.

EVA M. CLEWELL, OF CANTON, OHIO.

BRACE-WAIST.

1,235,292.

Specification of Letters Patent. Patented July 31, 1917.

Application filed August 21, 1912. Serial No. 716,118.

To all whom it may concern:

Be it known that I, EVA M. CLEWELL, a citizen of the United States, residing at Canton, in the county of Stark and State of Ohio, have invented a certain new and useful Brace-Waist, of which the following is a specification.

The invention relates to a brace and a waist, combined together, for supporting the breasts and the abdomen and also the skirts and the stockings of a person, and for carrying the weight thereof from the shoulders and bracing the back of the person; and the object of the improvement is to provide a combined garment which will sustain and support the human form in its natural contour without the use of a constricting waist belt, or an unyielding corset, and at the same time will develop the chest and induce deep breathing by holding the shoulders backward in normal position.

The object of the invention, thus set forth in general terms, is attained by the preferred embodiment thereof, illustrated in the accompanying drawings, forming a part thereof, in which—

Figure 1 is a front view in outline of a woman's form showing the waist-front and abdominal-support thereon;

Fig. 2 a similar rear view showing the lower portion of the waist-back broken away and exposing the back-brace and the rear portions of the waist-front and the abdominal support;

Fig. 3, a similar side view, showing the brace-back, the waist-front and the abdominal support, without the waist-back;

Fig. 4, a plan view of the abdominal-support.

Fig. 5, an inside view of the back-brace;

Fig. 6, a view like Fig. 3 with the lower portion of the waist-front broken away to expose the abdominal-support;

Fig. 7, a similar view showing the use of the abdominal-support with the waist-front and waist-back formed integral, without the use of a back-brace; and

Fig. 8, a similar view showing the back-brace combined with a modified form of abdominal-support, without either the waist-front or the waist-back.

Similar numerals refer to similar parts throughout the drawings.

The back-brace is made of two lateral sections 1 having their adjacent edges joined together in the median line by the series of

lace strings 2; each string of the series being laced through corresponding eyelets 3 along the median line edges of the back-brace sections, and the several strings being extended thence diagonally downward across the median line and through one of the series of guide-eyelets 4 transversely located along the lower edge in each brace-section 1, whence the strings on each side converge to 65 and are combined with the brace straps 5, as shown more particularly in Figs. 2 and 5 of the drawings.

Each lateral section 1 of the back-brace is extended upward to form the shoulder strap 6, which strap extends forward over the shoulder 7 of the person, and thence downward in front of the shoulder and rearward under the arm pit where it is connected to the side edge of the brace-section by means of the elastic strap 8, preferably passed through the laterally flattened link 9 on the ends of the shoulder strap 6, and having its upper end secured to the side edge of the brace-section 1, under the arm pit and its 80 lower end adjustably connected as by buckle 10, to the side edge of the brace-section, at or adjacent to the lower end thereof.

The lower end edges of the back-brace sections, are preferably inclined downward and inward from the side edges to form the pendant points 11, at the median line edges thereof; to which points the waist-band of a petticoat or a skirt can be pinned or otherwise secured, and the weight of the same will 90 be carried from the shoulders by the back-brace.

The abdominal-support 12, is made in the form of a wide band extending transversely across and under the abdomen 13 of the person, the ends of the band being preferably bifurcated to form the upper and lower lateral tongues 14 and 15, extending around the sides of the abdomen, which tongues are provided with the buckles 14^a and eyelets 100 15^a and are adjustably laced together by means of the strings 16.

The buckles 14^a of the upper tongue 14 of the abdominal-support 12, are engaged with the brace-straps 5 on the ends of the 105 lace-strings 2 of the brace-back, and the parts are so proportioned, arranged and adjusted that each side of the abdominal-support will be sustained by the shoulder strap 6 extending over the opposite shoulder of 110 the person and that the lace strings of the back-brace will draw the lateral sections

thereof toward each other, thereby holding the shoulders of the person backward by action of the shoulder straps 6, extending around the front of the shoulders 7.

5 The waist-front 17 or 17^a, is preferably made integral with or permanently secured to the waist-back 18 or 18^a, as shown in Fig. 7; but may be separable therefrom, as shown in Figs. 1, 3 and 6, so that the waist-back 10 need not be worn at all times with the other parts. When the waist-front and waist-back are made inseparable, the shoulder straps 19 thereof, extend over the shoulders of the person as shown in Fig. 7; but when 15 these parts are made separable, the shoulder straps 19^a of the waist-front are secured to the shoulder strap 6 of the back-brace, as by the buttons 20 on top of the shoulder, and the shoulder straps 19^b of the waist-back 20 may be connected to the straps of the waist-front by means of the same buttons. The waist-front 17 or 17^a extends downward from the shoulder straps with its side edges overlapping and preferably connected to the shoulder straps 6 of the back-brace, as by the buttons 20^a as shown in Fig. 1, and the side edges of the waist-front are furthermore provided with the waist-strings 21 located at or just above the waist-line of the person, which strings extend downward across each other at the middle of the back, and are respectively engaged with the lower tongues 15 on the opposite side of the abdominal-support, as by being 30 passed through the eyelets 15^a and then brought together and tied in the middle of the back, as shown in Fig. 2.

It is evident that the waist-front and the strings thereof serve to stretch and sustain 40 the abdominal-support, and particularly the lower side thereof, around and under the abdomen, for sustaining the same; and it is evident that the weight thereof will be carried by the waist strings 21, around the 45 small of the back and thence upward and across the waist-front by the shoulder straps 19 and 19^a and 19^b thereof to the opposite shoulder of the person; and also that the consequent stretching of the waist-front across the breasts serves to sustain the same, and also coöperates with the brace-back in throwing the shoulders backward into proper position.

The lower front portion 17^b of the waist-front, is preferably extended downward over the abdominal-support 12, and to the lower edge thereof is preferably secured the series of stocking supporting straps 22. The lower end portion 17^b of the waist-front is furthermore adjustably connected with the abdominal-support by means of the strings 23 laced through the series of eyelets 24 in the waist-front and 24^a in the abdominal-support. It is manifestly not essential or desirable in all cases, to make the

abdominal-support separate from the waist-front, but it is sometimes preferred to lace these parts together, as described and shown herein, so as to permit an adjustment of the parts with reference to each other.

The waist-back 18 or 18^a is formed with its side edges extending downward under the arm pits, to a connection with the waist-front, as by the buttons 20^b, whence the side edges extend downward to the lower end of the waist-back, located at or just above the waist-line of the person; and from the lower corners of the waist-back are extended the waist-straps 25, which are preferably engaged with the buckles 14^a on the ends of the upper tongues 14 of the abdominal support, as shown in Fig. 7.

From the foregoing description it is apparent that various combinations can be made among the several detachable parts, as for instance the abdominal support 12 can be worn with the waist-front and the back-brace, without the waist-back, as shown in Figs. 3 and 6; or all these parts can be worn together, as shown in Fig. 2; or the abdominal-support can be worn with the waist-front and waist-back, without the back-brace, as shown in Fig. 7; and finally, that the back-brace can be worn with the modified form of abdominal-support 12^a shown in Fig. 8, without either the waist-front or the waist-back, for supporting stockings by the straps 22^a when a positive support for the abdomen is not necessary, as in the case of undeveloped women.

It will be understood that when the waist-back is substituted for the back-brace, as shown in Fig. 7, it coöperates with the waist-front in sustaining the abdominal-support just like the back-brace, excepting only that the automatically adjusting lace-strings are omitted; so that the back-brace is in fact an adjustable waist-back, and may be broadly referred to merely as a waist-back when the adjustable feature is not involved, and the brace-straps of the back-brace may be broadly referred to as waist-straps. Furthermore, it will be understood that the waist-front, the abdominal-support and the back-brace are preferably provided with some kind of boning or other similar staying material, in the usual manner for staying these parts in proper position.

I claim:—

1. An adjustable back-brace composed of two lateral sections with shoulder-straps thereon, lace-eyelets along the adjacent edges and guide-eyelets along the lower edges of the sections, lace-strings in corresponding lace-eyelets and extending from the eyelets of one section diagonally downward through the guide-eyelets of the other section, and waist-straps extending from the combined lace-strings of each section; a waist-front having shoulder-straps on its upper end con-

nected to the shoulder-straps of the back-brace and having waist-strings on each side; and a transverse abdominal-support connected to the waist-front, and having one set 5 of lateral tongues engaged with the waist-straps on the same side and another set of lateral tongues engaged with the waist-strings of the opposite side.

2. An adjustable back-brace composed of 10 two lateral sections with shoulder-straps thereon, lace-eyelets along the edges and guide-eyelets along the lower edges of the sections, lace-strings in corresponding lace-eyelets and extending from the lace-eyelets 15 of one section diagonally downward through the guide-eyelets of the other section, and waist-straps extending from the combined lace-strings of each section; and an abdominal support having lateral tongues engaged 20 with the waist-straps on the same side.

3. A waist-front and a waist-back having connecting shoulder-straps on the upper ends, there being waist-strings on each side of the waist-front and waist-straps on the 25 lower corners of the waist-back, and an abdominal support having one set of lateral tongues engaged with the waist-straps of the same side and another set of lateral tongues

engaged with the waist-strings of the opposite side.

4. A waist-front having shoulder-straps on its upper end and waist-strings on each side, and an abdominal support connected to the waist-front and having lateral-tongues engaged with the waist-strings of the opposite side.

5. A back-brace having shoulder-straps on its upper end, adjusting means for the brace, waist straps at each side of the lower end of the brace associated with the adjusting means, and an abdominal support having lateral tongues engaged with the waist-straps on the same side.

6. An abdominal support having two tongues on each side, and a waist having 45 straps on each side of its back portion engaged with one set of tongues on the same side, and strings on each side of the front portion extended across the small of the back engaged with the other set of tongues 50 on the opposite side.

EVA M. CLEWELL.
